[57] CLAIM

The ornamental design for a Y connector for arthroscopic surgery, as shown and described.

DESCRIPTION

FIG. 1 is a perspective view of a Y connector for arthroscopic surgery showing my new design;

FIG 2 is a front elevational view thereof, the opposite side being identical thereto;

FIG. 3 is a top plan view thereof;

FIG. 4 is a side elevational view thereof, the opposite side being identical thereto;

FIG. 5 is a bottom plan view thereof; and

FIG. 6 is a perspective view thereof, the broken line showing is for illustrative purposes only and forms no part of the claimed design.

FIG. 3

FIG. 2

FIG. 1

FIG. 4

FIG. 5

FIG. 6
